OF CLEVELAND, OHIO.

APPARATUS FOR ADMINISTERING ANESTHETICS.

No. 883,987.

Specification of Letters Patent.

Patented April 7, 1908.

Application filed December 10, 1906. Serial No. 347,027.

To all whom it may concern:

Be it known that I, CHARLES K. TETER, a citizen of the United States, residing at Cleveland, in the county of Cuyahoga and State of Ohio, have invented a certain new and useful Improvement in Apparatus for Administering Anesthetics, of which the following is a full, clear, and exact description, reference being had to the accompanying drawings.

10 My invention relates to an apparatus for administering anesthetics and has for its object to provide a self-contained apparatus of this kind whereby the anesthetic may be intimately and conveniently mingled with a suitable proportion of oxygen; to provide, with an apparatus of this kind, a mixing chamber for the oxygen and anesthetic which shall be supplied through flexible receptacles; to provide means whereby the anesthetic may be warmed before inhalation; to provide means for muffling the sound produced by the passage of the anesthetic gas through the valves on its way to the mixing chamber; to provide means whereby several kinds of anesthetics may be employed with the same apparatus; and generally to simplify and improve the construction and efficiency of apparatus of this character.

Referring to the drawings, Figure 1 represents a perspective view of an apparatus constructed in accordance with my invention. Fig. 2 represents an enlarged plan view of the apparatus disclosed in Fig. 1. Fig. 3 represents a sectional view taken on the line 3—3 of Fig. 2. Fig. 4 represents a sectional view taken on line 4—4 of Fig. 2. Fig. 5 represents a perspective detail of the valve which controls the flow of oxygen into the mixing chamber. Fig. 6 represents a sectional detail on the line 6—6 of Fig. 5. Fig. 7 represents a sectional detail on line 7—7 of Fig. 2; and Fig. 8 represents a sectional detail taken on the line 8—8 of Fig. 7.

The apparatus comprises generally a supporting base, said base consisting of a tubular standard or upright 1, supported by the foldable legs 2. These legs are hinged to a collar 3 on the base of the standard.

4 denotes a collar slidable on standard 1 and provided with a set screw 5 for securing the same in any desired position on said standard. This collar has hinged thereto a series of links 6, one for each leg. The lower end of each link is pivotally connected to an intermediate portion of a leg 2, and the lower

end of each of said links 6 is offset from the upper portion thereof to permit the legs to be folded up into contact with the standard as well as downwardly into the position shown in the drawing, without obstruction by said links.

7 denotes a rod or standard which is slidably mounted within the hollow standard 1 and is connected at its upper end to an extension 8 projecting downwardly from the mixing chamber 9. This mixing chamber is provided with hollow arms 10, 10^a extending from opposite sides thereof and communicating therewith. Each of these arms is fitted into the mixing chamber, preferably by being threaded thereinto, and each of said arms is provided with an extension projecting into the body of the mixing chamber. At its outer end, each of the arms 10, 10^a is provided with a transverse arm 11 having at each end thereof a collar or yoke 12 for the reception of the neck 13 of a gas tank or cylinder 14. Each arm 11 is provided with a bore 15 extending longitudinally thereof from one collar to the other and is provided with a valve 16 at the central portion thereof and controlling the flow of gas from the bore 15 into a downwardly inclined bore 17, 17^a provided respectively in the arms 10, 10^a. As will appear more particularly from Fig. 8, the valve 16 is a three-way valve, enabling either or both branches of passageway 15 to be placed into and out of communication with passageway 17 or 17^a. At each end of bore 15 is a nipple 18 by which communication is established between the lateral port extending through the neck of the cylinder 14 and bore 15. Each of said cylinders is provided with the ordinary valve 19 and removable operating handle or key 20. A set screw 21 is provided for each of the collars or necks 12 for the purpose of clamping the neck of the gas cylinder with its lateral bore in operative relation to the nipple 18.

The inclined passageways 17, 17^a communicate with downwardly extending threaded necks 21, 21^a respectively, and to each of said necks is connected a bag 22, 22^a of rubber or similar material. The bags are preferably connected to the necks 21 by being threaded onto sleeves 23, 23^a, which in turn are threaded onto the lower ends of necks 21, 21^a, respectively. The lower end of passageway 17 is reamed out for the accommodation of a tubular connection 24, and to the lower

end of such connection there is fitted a tube of rubber or similar flexible material 25 which extends downwardly into the bag 22 to the bottom thereof, for a purpose to be 5 hereinafter described.

The neck 23 is provided with a lateral valved branch or connection 26, by means of which a large tank of anesthetic gas, as nitrous oxid, may be connected to the mixing 10 chamber without the employment of the cylinders 14.

27, 27^a denote valves interposed between passageways 17, 17^a and bags 22, 22^a and the tubular connections which project into 15 the mixing chamber. The valve 27 is of an ordinary type of hollow rotary valve having a port 28 in the cylindrical wall thereof communicating with the tubular connection 29 which is threaded into the 20 mixing chamber. The inner end of said connection is provided with a check valve, which may be conveniently formed by means of a thimble 30, which is threaded onto the inner end of 29 and is provided with a series 25 of openings 31, and a disk 32 loosely mounted in said thimble, seats being provided for said disk by the inner end of 29 and the flanged inner end of thimble 30.

The employment of connection 24 and 30 tube 25 is particularly useful in connection with the use of nitrous oxid or similar gaseous or volatile anesthetics. By extending the lower end of tube 25 to about the bottom of bag 22, the noise incident to the escape 35 of the nitrous oxid through the bore 15 and passageway 17 is muffled. Moreover, the nitrous oxid is discharged at the bottom of the bag and has to rise to the top thereof before passing into the mixing chamber, mingling in its course with the gas that is already contained therein. As is well known, the great expansion of the nitrous oxid from the liquid to the gaseous condition when it is liberated from the cylinder causes the gas to 40 be cooled. By admitting the cooled gas to the bottom of the bag 22, it is mixed with the gas which has been standing in said bag and which has been subjected to the temperature of the room, and the gas so admitted to the bag is warmed before being inhaled by the patient. For the bag 22^a, which receives oxygen from the cylinders 14^a, the employment of connection 24 and tube 25 is unnecessary. It is desirable, 45 however, to admit the oxygen to the mixing chamber in certain definite proportions.

For this purpose, I construct the valve 27^a as follows: The valve is provided with a large port 33 of substantially the diameter 50 of the connection 29^a. Merging with and extending laterally from said port is a slit 34 (see Figs. 3, 5, and 6), the length of said slit being substantially equal to the width of the inlet into the connection 29^a. The upper end 55 of valve 27^a is formed integrally with the

body thereof and is provided with a downwardly extending flange 35 surrounding a corresponding flange or shoulder 36 on arm 10^a.

The outer edge of the head 37 of flange 27^a is provided with a series of notches (see Fig. 70 2), such notched portion being of the same angular extent as slit 34. For convenience, ten such notches are provided and are numbered progressively from left to right.

38 denotes a spring extending vertically of 75 the valve casing and adapted to engage the notches in head 37 and to form therewith a stop and indicator. By turning the valve 27^a, the amount of oxygen being supplied to the mixing chamber may be regulated and 80 the proportion of oxygen so admitted may be determined by an inspection of the indicator. When the valve is turned so that the numeral 10 is in conjunction with spring 38, the full capacity of the slit 34 is being supplied to the 85 mixing chamber. Should it be desirable or necessary for any reason to increase this amount, the valve may be turned to bring the port 33 in register with connection 29^a. The connection 29^a projects into the mixing 90 chamber in the same manner as does connection 29 but is provided with a more sensitive form of check valve. The check valve in this case comprises a disk 39 adapted to seat 95 on the inner end of connection 29^a and provided with a stem 40 extending through a spider 41 within the connection. The end of stem 40 opposite the disk 39 is provided with a nut 42, and a spring 43 is interposed between said nut and the adjacent portion of 100 spider 41. It will be evident that by adjusting the nut 42, the tension of spring 43 may be varied to suit the requirements of the particular case.

To adapt my apparatus for the administering of ether, either alone or combined with oxygen, I provide the mixing chamber 9 with a tubular connection 44 and with means for supplying ether vapor through said connection. The inner end of the connection comprises a sleeve 45 threaded into the mixing chamber 9 and provided with a check valve 46, similar to valve 39. The connection 44 is provided with an elbow 47, the upper branch of which supports a vaporizing chamber 48, which is supplied with ether from a receptacle 49 having a valve 50 and a sight opening 51 adjacent the lower end of the valve. The upper branch of elbow 47 projects into a vaporizing receptacle 48 and is 110 there provided with a wire cage 52 for the purpose of preventing the gauze 53 in said chamber from obstructing the inlet to the upper branch of elbow 47. There is provided in the connection 54 between receptacles 48 and 49 an opening 55 for the admission of air to mingle with the ether vapor in chamber 48.

Projecting from the side of the mixing chamber opposite the connection 44 is a con- 120

nection whereby chloroform may be supplied, preferably mingled with the oxygen and nitrous oxid from the mixing chamber. This connection comprises a tee 56 threaded onto a nipple 57 projecting from the mixing chamber. Opposite ends of said tee are provided with connections 58 and 59, the former of which communicates with a receptacle 60 containing chloroform and the latter of which is provided with a flexible tube 61 leading off to an inhaler. The connection 58 is provided with a branched pipe communicating therewith, one of the branches 62 having a valve 63 and a downturned end 15 projecting through the cover of the receptacle 60 and into the body of said receptacle. The other branch 64 is offset from 62 and communicates with 62 intermediate of the valve 63 and connection 58. The branch 64 20 has a downward extension 65 which projects slightly through the cover of the receptacle 60, and said branch is provided with a valve 66. The end of branch 64 is provided with a flexible tube 67 whereby either chloroform 25 alone may be supplied to the mouth of the patient, through instrument 67^a when it is desired to operate on the mouth, or chloroform mingled with the gases in the mixing chamber may be so supplied. The tee is 30 provided with a valve 68, by means of which air may be forced to flow through either of the branches 62 or 64 into the receptacle 60, instead of the gases from the mixing chamber, if this should be so desired.

35 By means of the chloroform receptacle 60 and the connections therewith, chloroform may be added to the mixture of nitrous oxid and oxygen flowing through the tube 61 in certain cases where this may be required.

40 The chloroform may be conveniently added by connecting the tube 67 to the inhaler. By opening the valve 63, part of the mixture of nitrous oxid and oxygen which enters the tee 56 will pass through pipe 62 and the downward extension thereof into the chloroform receptacle 60, and will there be charged with vapors of chloroform and the mixture thus produced will be conducted through connection 65 and tube 67 to the point of use. By 45 opening the valve 66, the mixture of nitrous oxid and oxygen which passes through the connection 58 is divided, only about half of the same passing into the chloroform receptacle. The result is to proportionately reduce the amount of chloroform supplied through tube 67. By proper manipulation of valves 63 and 66, the proportion of chloroform supplied through tube 67 may be varied to suit the requirements of the case. By 50 leading tube 67 to the inhaler 61^a on tube 61, as indicated by dotted lines, Fig. 1, this mixture of chloroform, nitrous oxid and oxygen may be mingled with the mixture of the latter two gases flowing through the tube 61.

55 The interposition of the flexible bags be-

tween the gas cylinders and the mixing chamber enables the gases to be mixed in accordance with the symptoms of the patient and the exigencies of the operation. By keeping the oxygen bag and the nitrous oxid bag at 70 about the same distention (through the manipulation of the valves 19) the two gases are supplied to valves 27 and 27^a at substantially even pressure, and the proportions of 75 said gases delivered unto the mixing chamber may be accurately regulated by valves 27, 27^a. Furthermore the pressure exerted by the elastic walls of said bags on the gases contained therein assists the respiration of the patient by relieving the respiratory muscles from stress whether only nitrous oxid and oxygen be used alone or in combination with another anesthetic. At the same time, the bags permit the use of a small mixing chamber, contributing to the compactness 80 and portability of the apparatus.

85 It will be apparent, from the foregoing description taken with the drawings, that I have produced a complete, self-contained, and portable apparatus whereby various 90 anesthetics may be conveniently and scientifically administered, either alone or conjointly with oxygen and other anesthetics, and one that is free from the objectionable features of other apparatus of this character 95 with which I am acquainted.

100 Important features of my invention are the adaptability of the same for the administration of various kinds of anesthetics; the employment of a mixing chamber in conjunction with the distensible bags; the muffling of the noise of the expanded nitrous oxid; the provision of means for warming the same prior to administration; means for mingling 105 the oxygen with the anesthetic in definite proportions; the arrangement of parts whereby ether or chloroform may be administered through the same apparatus by which the nitrous oxid and oxygen are supplied; and the provision of a complete, self-contained 110 apparatus whereby the administration of various anesthetics may be scientifically accomplished.

115 Having described my invention, I claim:

1. In an apparatus for administering anesthetics, the combination of a chamber, a tubular arm projecting from and communicating therewith, said arm having intermediate the ends thereof a downwardly projecting branch, a flexible bag or receptacle carried 120 by said branch, a yoke or support for an anesthetic cylinder carried by the outer portion of said arm, a passageway extending from said yoke or support into the downward extension of said arm, a tube extending from said branch to the lower portion of the flexible bag, and an outlet from said chamber. 125

130 2. In an apparatus for administering anesthetics, the combination of a chamber, a tubular arm projecting from and communicat-

- ing therewith, said arm having intermediate the ends thereof a downwardly projecting branch, a flexible bag or receptacle carried by said branch, a yoke or support for an anesthetic cylinder carried by the outer portion of said arm; a downwardly extending passageway leading from said yoke or support into the downward extension of said arm, a flexible tube extending from said branch to 10 the lower portion of the flexible bag, and an outlet from said chamber.
3. In an apparatus for administering anesthetics, the combination of a chamber, a cylinder or receptacle for anesthetics, a duct 15 extending between said cylinder or receptacle and said chamber, a flexible bag interposed between said cylinder or receptacle and said chamber, means for admitting the anesthetic supplied from the cylinder or 20 receptacle to the bottom of the bag, and an outlet from said chamber.
4. In an apparatus for administering anesthetics, the combination of a chamber, a cylinder or receptacle for anesthetics, a duct 25 extending between said cylinder or receptacle and said chamber, a flexible bag interposed between said cylinder or receptacle and said chamber, means for causing the anesthetic supplied from the cylinder or 30 receptacle to travel substantially the length of the bag in its passage to the chamber, and an outlet from said chamber.
5. In an apparatus for administering anesthetics, the combination of a chamber, a 35 tubular arm projecting therefrom, said arm having a connection, a flexible bag or receptacle supported by said connection, a support or yoke for an anesthetic cylinder on said arm, a duct extending between said cylinder and said bag, means for causing the anesthetic supplied to said bag to travel 40 substantially the length of the bag before entering the connection, and an outlet from said chamber.
- 45 6. In an apparatus for administering anesthetics, the combination of a mixing chamber, a tubular arm projecting therefrom, said arm having a connection, a flexible bag or receptacle supported by said connection, a support or yoke for an anesthetic cylinder on said arm, a duct extending between said cylinder or receptacle and said bag, means for causing the anesthetic supplied to said bag to travel substantially the length of the bag before entering the connection, means for supplying oxygen to said chamber, and an outlet from said chamber.
- 55 7. In an apparatus for administering anesthetics, the combination of a chamber, a tubular arm projecting therefrom and communicating therewith, said arm having a downwardly extending branch, a flexible bag connected to said branch, an extension of said arm projecting beyond the downward exten-

sion and provided with a support for an anesthetic receptacle, the latter extension having a passageway extending from said yoke or support into the downward extension, a flexible tube communicating with said passageway and extending nearly to the bottom of the bag, a valve for controlling the supply of anesthetic from the receptacle to the bag, and an outlet from said chamber.

8. In an apparatus for administering anesthetics, the combination of a mixing chamber, tubular arms projecting therefrom and communicating therewith, said arms having each a branch, a flexible bag connected to each of said branches, an extension projecting beyond each of the said branches and 75 provided with a yoke or support, said extensions having each a passageway extending from said yoke or support into the bag-supporting branch, a flexible tube communicating with one of said passageways and extending nearly to the bottom of the corresponding bag, a valve in each of said passageways, and an outlet from said chamber.

9. In an apparatus for administering anesthetics, the combination of a chamber, an arm projecting therefrom and provided with a transverse hollow arm having a pair of yokes or supports for tanks or cylinders, each of said arms being provided with a passageway extending from the passageway in the 90 transverse arm to the mixing chamber, a valve controlling the flow of fluid from either or both tanks or cylinders on each transverse arm through the passageway communicating therewith, and an outlet from 95 said chamber.

10. In an apparatus for administering anesthetics, the combination of a chamber, a tubular arm projecting therefrom and communicating therewith, said arm having a 105 branch intermediate the ends thereof, a flexible bag carried by said branch, a pair of yokes or supports at the outer end of said arm, said arm having a passageway extending from each of said yokes or supports to the central portion thereof and a passageway extending from the junction of the former passageways to the bag or receptacle, a valve at the junction of the three passageways, and an outlet from said chamber.

11. In an apparatus for administering anesthetics, the combination of a mixing chamber, a pair of tubular arms projecting therefrom and communicating therewith, each of said arms having intermediate the 120 ends thereof a branch, a flexible bag carried by each of said branches, a pair of yokes or supports at the outer end of each of said arms, each of said arms having a passageway extending from each of said yokes or supports to the central portion thereof and a passageway extending from the junction of the former passageways to the corresponding

bag or receptacle, a valve in each arm at the junction of the three passageways, and an outlet from said chamber.

12. In an apparatus for administering anesthetics, the combination of a mixing chamber, a pair of arms projecting therefrom, each of said arms having adjacent its outer end a pair of yokes or supports for gas tanks and being provided with a passageway connecting said yokes and a downwardly inclined passageway extending from the former passageway, a connection with which each of said inclined passageways communicates, a flexible bag communicating with each of said extensions, each of said arms having also a passageway extending between the connection and the mixing chamber, a valve interposed between each of said bags and the mixing chamber, and a check valve interposed between each of the former valves and the mixing chamber.

13. In an apparatus for administering anesthetics, the combination of a mixing chamber, said chamber having connections for supplying thereto oxygen and a gaseous anesthetic, valves in said connections, a vaporizing receptacle for liquid anesthetic said receptacle having an opening therein, a tubular connection extending from said opening to the mixing chamber, reticulated material in the said receptacle, and a cage interposed between such material and the opening in said receptacle.

14. In an apparatus for administering anesthetics, the combination of a mixing chamber, said chamber being provided with connections for the supply thereto of oxygen and a gaseous anesthetic, valves in said connections, an outlet pipe leading from said chamber, an inhaler on said pipe, a receptacle for liquid anesthetic, a connection between said receptacle and said inhaler, and means for diverting a portion of the mixed gases from the mixing chamber through said receptacle, whereby said gases may be charged with the vapor of anesthetic in said receptacle and added to the mixture of gases being supplied to the inhaler.

15. In an apparatus for administering anesthetics, the combination of a mixing chamber, said chamber having connections for supplying oxygen and an anesthetic gas thereto, valves in said connections, a receptacle for liquid anesthetic, an outlet connection extending from said mixing chamber to said receptacle, and a valve in said connection.

16. In an apparatus for administering anesthetics, the combination of a mixing chamber having a connection for oxygen and a connection for an anesthetic gas, a valve in

each of said connections, an outlet connection extending from said chamber, a receptacle for liquid anesthetic communicating with said outlet connection, and a second outlet connection extending from said chamber.

17. In an apparatus for administering anesthetics, the combination of a mixing chamber having connections for supplying oxygen and an anesthetic gas thereto, valves in said connections, a receptacle for liquid anesthetic, an outlet connection extending from said chamber to said receptacle, said connection having two branches, one of said branches being provided with a valve and having a connection, intermediate of the ends thereof, communicating with said receptacle.

18. In an apparatus for administering anesthetics, the combination of a mixing chamber, said chamber being provided with connections for supplying oxygen and a gaseous anesthetic thereto, valves in said connections, a receptacle for liquid anesthetic and an outlet connection leading from the chamber thereto, said outlet connection being branched, one of said branches being provided with a pipe for supplying anesthetic to the point of use and the other branch having its end extending into the receptacle, and means for causing a portion or the entire amount of mixed gases passing through the outlet connection to pass through the latter branch and through the receptacle before reaching the other branch.

19. In an apparatus for administering anesthetics, the combination of a mixing chamber having connections for supplying oxygen and gaseous anesthetic thereto, valves in said connections, an outlet connection comprising a tee communicating with said chamber, said tee having two discharge pipes connected thereto, and a receptacle for liquid anesthetic connected to one of said pipes.

20. In an apparatus for administering anesthetics, the combination of a mixing chamber having connections for supplying oxygen and a gaseous anesthetic thereto, valves in said connections, a tee communicating with said mixing chamber and having a valve for the admission of air thereto and a pair of connections, discharge pipes on said connections, and a receptacle for liquid anesthetic communicating with one of said pipes.

In testimony whereof, I hereunto affix my signature in the presence of two witnesses.

CHARLES K. TETER.
